UNITED STATES PATENT OFFICE

2,627,298

CONVERTIBLE NURSERY FURNITURE

Roy W. Brown, Brandon, Manitoba, Canada

Application September 19, 1947, Serial No. 774,914

1 Claim. (Cl. 155—22)

1

My invention relates to nursery furniture, an object of the invention being to provide an article of nursery furniture which is particularly adapted for small homes, apartments and the like and is convertible to a variety of uses according to the desires of the parents and according to the age of the child.

Specifically, my article of furniture may be employed as a bassinette or crib either rockable or wheeable, being a low-type chair in which the infant may be fed or may play on the tray provided, such chair being also either rockable or wheeable, a "walker" or in other words a device in which the child may be placed for training in walking, a carriage, a sleigh, a tea-wagon, or a night or bed table.

A further object is to provide an article of furniture of the character herewithin described which is of conspicuously simple construction rendering the same susceptible to merchandising at a low price, and which is convertible into the various uses aforesaid quickly and readily without anything more than the most rudimentary instruction leaflet or label.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which—

Figure 1 is a plan view of my article of nursery furniture.

Figure 2 is a cross-section on the line 2—2 of Figure 1.

Figure 3 is a cross-section on the line 3—3 of Figure 2.

Figure 4 is a fragmentary detail illustrating the manner in which my wheel assembly locking rods engage recesses provided therefor in the associated guideways.

Figure 5 is a longitudinal vertical cross-section as per Figure 2 of an alternative embodiment of my invention.

Figure 6 is a fragmentary underside plan of the central area of the embodiment of Figure 5 illustrating the manner in which the wheeling assemblies may be preserved in the out-of-use position.

In the drawings like characters of reference indicate corresponding parts in the different figures.

My invention comprises a rectangular en-

2

closure collectively designated 1 and comprised of the pair of side walls 2 and end walls 3 and 4. The foregoing walls are secured to framing members 5 and 6, the latter taking the form of rockers.

The framing members 5 are of the cross-sectional configuration best depicted in the accompanying Figure 3 and are longitudinally grooved at 7 to receive at the right-hand end thereof (with respect to the accompanying Figures 1 and 2) the slidably removable tray 8 bordered by the flanges 9 and 10. In this connection it is to be noted that the grooves 7 are open ended or extend from end to end of the framing members 5, 15 so that the tray 8 can be slid longitudinally in and out of the members 5. A rear horizontal panel portion 11 similarly provided with a flange 12 is positioned to the rear of the back-board 13.

The back-board 13 rests via the lower edge thereof on a pair of inclined slats 14 lying parallel with and adjacent to the side walls 2. Upon these slats is also supported a seat-board 15 as clearly depicted in Figure 2 from which it will be seen that the back-board may be adjusted as to its position within the enclosure 1 by means of the transversely aligned, spaced and diagonally disposed pairs of slots 16, 16A etc. of which pairs of slots as many as desired may be formed in the members 5.

30 A pair of transversely aligned recesses 17 are provided in the upper edges of the rockers 6 to receive a removable foot-board 18, and for the amusement of the infant, I secure to the side walls 2 and across platform 8, a bead rod 19. It will be observed from Figure 2 that the upper edge of the foot board 18 rests against the vertical side members 21 hereinafter described.

35 Positioned for vertical sliding movement against the interior surfaces of the end walls 3 and 4, and within guideways 20 formed between the aforesaid end walls and vertical side members 21 secured against side walls 2 are wheeling assemblies designated 22. These wheeling assemblies each consists of a horizontally oblong rectangular frame 23 composed of the upper and lower horizontal rails 24 and 25 and the side rails 26.

40 The aforesaid frame is enclosed by panels 27 and 28, and positioned within the aforesaid frames are means for securing the wheeling assemblies in retracted or elevated position, or alternatively in projected position.

45 The means for maintaining my wheeling assemblies in retracted or projected position as stated in the immediately preceding paragraph 50 consists in the provision of a vertical slot 29 in

each of the upper rails 24, through which extend the vertically angulated portions 30 of retractable dogs in the form of oppositely endwise shiftable rods 31 normally held outwardly projected by the springs 32 the outer ends whereof are anchored to downwardly projecting eye-bolts 33 secured to the underside of rail 24, while the inner ends of the aforesaid springs are anchored to the upwardly projecting portions 30.

The upwardly projecting portions 30 terminate in grips 34 for the convenient manipulation thereof, and it is to be understood that the outer ends of the rods 31 extend through pairs of aligned apertures 35 in the side rails 28. It is to be observed that positioned within the guideways 20 are filler strips 36 as depicted in the accompanying Figure 4 having upper and lower apertures 36^A and 36^B into which the rods 31 may be projected in the retracted and lowered position of the wheeling assemblies respectively.

Secured for swivelling movement to the rails 25 are castors 37 and from the foregoing description it will be understood that upon gripping the members 34 and squeezing, the rods 31 move inwardly to disengage the associated wheeling assembly whereby the same may be projected and my device elevated above the rockers 6. By reference to Figure 2 it will be noted that sleigh runners 38 may if desired be secured against the under edges of rockers 6 by means of the studs 39 which extend through blind apertures 40 formed in the said rockers.

In view of all the foregoing it will now be explained that if it is desired to use my invention as a bassinette or crib, back-board 13 will be removed and the seat-board 15 moved leftwardly. Thereafter foot-board 18 will be placed across slats 14 at the right-hand end (with respect to Figure 2) of the leftwardly moved seat-board to provide for a continuous bed or panel. If it is desired to use the device as a walker, the footrest 18 is removed, the wheeling assemblies 22 are lowered and the seat-board and backboard may be removed or allowed to remain according to choice. The child may then stand within the enclosure 1, and by holding on to the sides, propel the device and thus gain self-instruction in the art of walking.

If it is desired to use my device as a tea-wagon, the wheeling assemblies will be lowered and the back-board 13 removed. Same will then be inserted into slots 7 with the curved upper edge 41 at the right-hand end (with respect to Figure 1). Tray 8 will of course have been previously removed, and thereafter re-inserted when it will be found that the curvature of the flange 9 is complementary to that of edge 41 so that a continuous table top is provided.

In the accompanying Figures 5 and 6 I have depicted an alternative manner of projecting and retracting the wheeling assemblies 2. In this modification the guide members 21 of my first embodiment are eliminated, the wheeling assemblies being pivoted at the upper corners thereof for rotary movement at the point 43.

Each wheeling assembly may be maintained in the vertical position by means of a conventional break-joint brace 44 such as is commonly employed in connection with bridge-tables and the like, and any of several means may be employed to maintain the wheeling assemblies in the re-

tracted or horizontal position, such, for example, as the rotatable tie-bar 45 one end of which is secured at 46 to one of the wheeling assemblies, the other end being hooked as at 47 to engage a stud 43 on the other wheeling assembly. In all other respects it is to be understood the embodiment of Figures 5 and 6 is similar to that depicted in Figures 1 to 4 inclusive.

In conclusion it may be stated that by turning my device up on one end so that either one of the end walls 3 or 4 constitutes a table top, a night or bed table may be formed, and since various modifications can be made in my invention as hereinabove described, and many apparently widely different embodiments of same made within the spirit and scope of the claim without departing from such spirit and scope, it is intended that all matter contained in the accompanying specification shall be interpreted as illustrative only and not in a limiting sense.

What I claim as my invention is:

In an article of furniture of the class described, a vertically walled, horizontally rectangular and oblong enclosure wherein the longer side walls are rocker mounted, a pair of wheeling assemblies within said enclosure, means mounting each of said wheeling assemblies for retraction within, and extension from said enclosure, said assemblies each including a substantially rectangular plate, and a pair of spaced castors secured at the lower edges of each of said plates, said mounting means enabling said wheeling assemblies to be pivotally mounted for rotation between the vertical and the horizontal adjacent the lower edges of the end walls of said enclosure, said wheeling assemblies, in the horizontal position, being nested in opposition between said end walls, and means for maintaining said wheeling assemblies in the retracted position within said enclosure and further means for maintaining said assembly in the extended position from said enclosure, said first mentioned means including a rotatable tie-rod secured at one end thereof to one of said wheeling assemblies and being detachably secured by the other end thereof to the other of said wheeling assemblies, said last mentioned means including a break-joint brace extending between the side walls of said enclosure and said wheeling assemblies.

ROY W. BROWN.
